(57) **CLAIM**

The ornamental design for a trail camera, as shown and described.

DESCRIPTION

FIG. 1 is a front perspective view of a trail camera, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged portion view taken from encircled portion labeled, “FIG. 9,” in FIG. 1; and,

FIG. 10 is an enlarged portion view taken from encircled portion labeled, “FIG. 10,” in FIG. 2.

The dashed-dot-dot lines form the boundary of the enlarged portion view of FIGS. 9 and 10 in FIGS. 1 and 2 and form no part of the claimed design. The even dashed broken lines shown in the drawings are included for the purpose of illustrating portions of the trail camera that form no part of the claimed design.
